UNITED STATES PATENT OFFICE.

FREDERICK MERTSHEIMER, OF DENVER, COLORADO.

VALVE.

SPECIFICATION forming part of Letters Patent No. 740,157, dated September 29, 1903.

Application filed February 24, 1903. Serial No. 144,749. (No model.)

To all whom it may concern:

Be it known that I, FREDERICK MERTSHEIMER, of Denver, county of Arapahoe, and State of Colorado, have invented a new and useful Improvement in Valves, of which the following is a specification.

This invention relates to valves, and has reference more particularly to what are known in the art as "blow-off" valves, which are used in connection with locomotive or other boilers. In the use of these valves it frequently happens that scale from the boiler will lodge between the valve and its seat, so that the valve is prevented from effectually closing, and a leakage of water from the boiler results. It is the aim of my invention to avoid the liability of leakage from such causes; and my invention consists in the combination, with a valve-casing having an opening in communication with the boiler and provided with a valve-seat, of a plug-valve adapted to said seat and having in its side an opening arranged to be brought in register with that in the valve-casing or adjusted out of register with it, and a disk valve situated within the plug-valve and adapted to be seated on a valve-seat independent of that of the plug-valve and controlling the passage of fluid through the casing and the opening in the plug-valve, and means for operating said valves independently, whereby in the event of leakage of the disk valve the plug-valve may be turned and cutoff communication with the boiler, after which access may be had to the disk valve and the leakage corrected.

The invention consists also in the details of construction and combination of parts hereinafter described and claimed.

In the accompanying drawings, Figure 1 is a vertical longitudinal section through my improved valve. Fig. 1 is a similar view showing the parts in a different position. Fig. 3 is a side elevation of the valve. Fig. 4 is a top plan view of the same.

Referring to the drawings, 1 represents a valve-casing, which is provided in its side with an opening 2 in communication with the boiler and in its bottom with an opening 3 for the escape of the water. This casing is tapered on its interior above the opening 3, so as to form a tapered valve-seat in which is seated and mounted to rotate a plug-valve

7, having in its side an opening 8, which may be brought in register with the opening 2 in the valve-casing to permit the passage of the fluid, as shown in Fig. 1, or which may be adjusted out of register with said opening, so as to close the communication through the valve-casing, as shown in Fig. 2. This plug-valve is hollow and is formed with an extension or neck 9, which passes upward through the top of the casing, within a stuffing-box 10 therein, and has its end exposed on the outside of the casing, where it has attached to it a laterally-extending handle 11, by which the valve may be turned so as to open or close communication, as desired. This handle is furnished with a downwardly-extending pin 12, which is adapted to contact with a stop lug 13 on the side of the valve-casing, so as to indicate the position of the valve whether open or closed.

14 represents a disk or lift valve which is situated within the plug-valve and which is adapted to seat against a sloping valve-seat 6, situated below the lower end of the plug-valve. This lift-valve is adapted to be moved longitudinally to and from its seat to open or close communication through the casing, and for this purpose the interior of the plug-valve is large enough to permit the lift-valve to move across and clear of the opening 8, so as to give the water and scale a clear and unobstructed passage from the boiler to the outside. This movement of the lifting-valve is effected by means of a stem 13^x in the form of a rod attached at its lower end to the valve and extending within the neck 9 of the plug-valve and through the same and through a stuffing-box 14^x in said neck and through its upper end, where it is provided with a slotted head 15, having a bolt 16 therein for the engagement of a lifting-lever. This valve 14 is employed to normally control the passage of the fluid through the casing and incidentally through the plug-valve, which latter when in operation is adjusted to an open position, as shown in Fig. 1. If, however, there is a leakage between the seat of the valve 14 and the valve such as would be caused by the lodgment of a scale the plug-valve is turned on its seat to the position shown in Fig. 2, thereby adjusting its opening out of register with the opening 2 in the valve-casing and cutting off com-

munication with the boiler. Access may then be had to the disk valve and its seat through the bottom of the casing, which is provided with a threaded neck, to which an elbow 16⁵ is secured by a cap-nut 17.

It will be observed that both valves close against seats formed on the casing, which seats are independent of each other, and that both valves are provided with extensions or stems which project through the casing to the outside, where they are adapted to be operated independently, a stuffing - box surrounding the stem of the plug-valve, between it and the casing, and a second stuffing-box 15 surrounding the stem of the lift-valve, between it and the stem of the plug-valve.

In order that when the plug-valve is turned to establish communication through the casing in the normal operation of the valve, as 20 shown in Fig. 1, it may be firmly held in this position, I provide a set-screw 20, which is tapped through the top of the casing and has its lower end in position to bear against the upper side of the plug - valve. When the 25 plug-valve is to be turned to close communication through the casing, this set-screw is unscrewed, which will release the valve and permit it to be turned.

Having thus described my invention, what 30 I claim is--

1. In a valve the combination with a casing having a passage - way through it and provided with a valve - seat, of a plug - valve formed to fit said seat and having an opening in its side adapted to be brought in register with the passage-way in the casing, a lift-valve situated within the plug-valve and movable freely across its side opening, a valve-seat on the casing below the plug-valve and independent thereof against which the lift-valve 35 is adapted to seat, means for operating the lift-valve from the outside of the casing, and means for operating the plug-valve also from the outside of the casing and independently 40 of the lift-valve.

2. In combination with a valve-casing having an opening therethrough, a rotary plug-valve mounted in the casing and provided with an opening adapted to register with that 50 in the casing, a hollow stem connected with the plug - valve and extending through the casing to the outside, a stuffing - box surrounding said stem within the casing, a lift-valve situated centrally within the plug-valve 55 and movable freely therein, a valve-seat on

the casing against which the lift-valve is adapted to close, a stem on the lift-valve extending through the hollow stem of the plug-valve to the outside, a stuffing-box within the hollow stem and surrounding the stem of the lift-valve, and means for operating said valve-stems independently of each other. 60

3. In combination with a valve-casing having a passage-way therethrough and provided with a tapered valve - seat, a tapered rotary 65 plug-valve adapted to said seat and arranged to be adjusted to open or close the opening through the casing, means for operating the plug-valve from the outside of the casing, a locking device mounted on the casing and 70 adapted to engage the plug-valve within the casing, and acting to force the plug-valve on its seat, a lift-valve situated within the plug-valve, a valve-seat on the casing with which the lift - valve is adapted to coöperate, and 75 means for operating said valves independently of each other.

4. In combination with a valve-casing having a passage-way therethrough and provided with a tapered seat, a rotary plug - valve 80 adapted to said seat and formed with an opening arranged to be adjusted in communication with the passage and adapted also to close said passage, means for locking the plug-valve normally in an open position, a 85 hollow stem on the plug - valve extending through the casing to the outside, a handle on the hollow stem, a stop on the valve-casing adapted to be engaged by said handle, a second valve situated within the plug-valve, 90 a valve - seat on the casing below the plug-valve and independent of the seat of the plug-valve against which the second valve is adapted to close, said second valve being movable to and from its seat independently 95 of the plug-valve, and serving to control normally the passage of fluid through the plug-valve and casing when the former is in an open position, and a stem on the second valve 100 extending through the hollow stem of the plug - valve to the outside of the casing and formed with an operating-head.

In testimony whereof I hereunto set my hand, this 10th day of February, 1903, in the presence of two attesting witnesses.

FREDERICK MERTSHEIMER.
